UNITED STATES PATENT OFFICE.

JAMES F. LEWIS, OF ROCKY HILL, KENTUCKY.

COMBINED CULTIVATOR AND SCRAPER.

SPECIFICATION forming part of Letters Patent No. 236,343, dated January 4, 1881.

Application filed August 23, 1880. (No model.)

To all whom it may concern:

Be it known that I, JAMES F. LEWIS, a citizen of the United States, residing at Rocky Hill, in the county of Barren and State of Kentucky, have invented certain new and useful Improvements in Combined Cultivator and Scraper; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to a cotton-scraper and cotton-cultivator capable of adjustment and use in different agricultural pursuits; and the novelty consists in the construction and arrangement of parts, as will be more fully hereinafter set forth.

The device is bolted together in such a manner that it may be readily taken apart and changed, as will be seen, from a one-horse cultivator to a two-horse scraper, cultivator, or plow.

In carrying out my invention I employ the construction shown in the accompanying drawings, which form a part of this specification, and in which—

Figure 1 is a side elevation, and Fig. 2 a top plan view.

Referring to the drawings, A represents the main beam, to which are secured the handles A', as shown. From the forward end of the beam 35 A extend braces b, which are secured to double plates B, having perforations b', which receive removable bolts, which secure upon one side the beam D, and upon the other side the beam E.

C represents a cross-plate, having perforations c, as shown.

The beam D may be secured by pin-bolts, easily removable, to the inner holes in the plates

B and the outer holes in the plate C, when the device is arranged for a two-horse cultivator, and reversed when arranged for a one-horse 45 cultivator, and the same adjustability is true of the beam E.

The beam E is provided with two lateral slots, e, by means of which the said beam may be set forward, as shown in Fig. 2, for a scraper and cultivator, or be set back for a cultivator, the perforated plate C c working in either slot e, as desired.

F represents the plow-shank, and f' the plow. These plows are readily removed, and 55 are adapted to be interchanged to adapt the device to the different purposes for which it is intended.

G represents a bifurcated standard secured one to each of the beams D and E by means 60 of a bolt, which operates in the slot g and renders the standard vertically adjustable. Between the bifurcated extremities of the standard G is journaled the colter H, and a brace, H', extends from the shaft of the colter H upward and backward, and is secured to the beam, as shown.

From this description the operation is obvious.

What I claim as new, and desire to secure 70 by Letters Patent, is—

The herein-described cultivator, consisting of the beam A, the perforated plates B C, the laterally-adjustable beams D E, the bifurcated slotted standards G, braces H', and colters 75 H, the said beam E adapted to be adjusted backward or forward to form a cultivator or scraper, as described.

In testimony whereof I affix my signature in presence of two witnesses.

JAMES F. LEWIS.
